UNITED STATES PATENT OFFICE.

MICHAEL F. CAREY, OF ALBANY, NEW YORK.

DESIGN FOR A PLAYING-CARD.

SPECIFICATION forming part of Design No. 27,905, dated November 30, 1897.

Application filed September 29, 1897. Serial No. 653,524. Term of patent 7 years.

To all whom it may concern:

Be it known that I, MICHAEL F. CAREY, of Albany, in the county of Albany and State of New York, have invented and produced a new and original Design for a Playing-Card, of which the following is a full, clear, and exact description.

Reference is to be had to the accompanying drawing, forming a part of this specification, in which the figure is a face view of a playing-card, showing the design.

The leading feature of the design consists in diagonal lines A, extending over the face of the card and dividing the said face into fields 15 B of an approximately triangular shape.

A minor feature of the design consists in the diagonal lines being arranged in pairs and forming narrow diagonal strips C, having widened ends C', formed by the said lines being curved in opposite directions to the side edges of the card, as plainly indicated in the drawing.

I claim—

The design for a playing-card as herein shown and described.

MICHAEL F. CAREY.
